MILLER REESE HUTCHISON, OF NEW YORK, N. Y., ASSIGNOR TO LOVELL-McCONNELL MANUFACTURING COMPANY, A CORPORATION OF DELAWARE.

HORN OR SIGNAL DEVICE.

1,087,538.

Specification of Letters Patent. Patented Feb. 17, 1914.

Application filed December 7, 1908. Serial No. 581,902.

To all whom it may concern:

Be it known that I, MILLER REESE HUTCHISON, a citizen of the United States, and a resident of the city of New York, in the county and State of New York, have invented certain new and useful Improvements in Horns or Signal Devices, of which the following is a specification.

My present invention relates to horns of the type commonly used on automobiles, launches, etc., for the purpose of giving an alarm or signal, and particularly to diaphragm actuated horns. The conditions of use usually require that such horns be mounted in exposed positions and usually arranged so that the diaphragm is vertical and the mouth of the horn forwardly directed so as to throw the sound in the direction of movement. A horn so arranged on an automobile traveling at high speed is particularly exposed, and is in position to collect flying particles of dirt, pebbles, mud, rain, etc. The same thing may happen in the washing of an automobile with a hose as commonly practised. In such cases, the foreign matter collects in the space between the diaphragm and the diaphragm case, thereby causing the note of the horn to be muffled and comparatively useless. Moreover, a body of water remaining in such space for any length of time tends to corrode the metal and to soak through the joints and packing into the interior where it may damage the operating mechanism. For the above reasons it is common to enclose the operating parts of the horn in a tight casing and to protect the mouth of the horn or projector by a screen.

In my prior applications, Serial No. 280,910 and Serial No. 494,399, I have described and claimed a separate drain hole arranged in the front section of the case leading from the lower portion of the space between it and the diaphragm, whereby water and other foreign matter may be drained or expelled from said cavity. Screens do not keep out water, and they do tend to dampen the sound of the horn. Drain holes are satisfactory, but they have a slight tendency to impair the note. Hence, it may become desirable to avoid either of these expedients, though, of course, this is less likely in the case of the mechanically

actuated diaphragm horn shown in prior application, Serial No. 494,399.

My present invention, therefore, contemplates an arrangement of the diaphragm and of the horn or resonator used to amplify and project the sound, whereby the cavity between the diaphragm and front case may be effectively drained through the projector opening, notwithstanding the fact that the mouth of the projector is forwardly directed. This is accomplished by arranging the diaphragm and the diaphragm inclosing section of the case in a position sufficiently near the horizontal so that foreign matter forced against the diaphragm will drain out of the case by gravity, and by having the horn or projector curved around toward parallelism with the diaphragm so that the sound is projected in a direction sufficiently approximating the horizontal. The curvature of the bottom wall of the horn is preferably such that there is a continuous gravity drainage from the diaphragm case to the mouth of the horn. The drainage pitch of the horn need not be great because the diaphragm forms a tight closure for the rear end of the horn, thereby preventing any possibility of updraft which would tend to oppose the free drainage by gravity. Moreover, in the case of an automobile horn, the changes of position of the automobile due to down grades of the road will serve to effectively drain a diaphragm case, although the drainage pitch of the inner surface of the case may not be sufficient to completely discharge water when the automobile is standing on a level or is traveling up hill.

In the drawings, Figure 1 is a side elevation showing the diaphragm and the sound projector in vertical central section; Fig. 2 is a front elevation showing one means of securing the horn in the desired position.

In the drawings the instrument comprises a rear case 1, inclosing any desired mechanical, electric or electromagnetic, means for vibrating an acoustic diaphragm 2. The latter is clamped between suitable surfaces 4 and 5 on the rear section of the case 1 and on the diaphragm section 3, suitable washers 6 and 7 being provided for cushioning the diaphragm and for rendering the joint water-tight. In the form shown the diaphragm section 3, the diaphragm, and

washers 6 and 7 are positioned within a downwardly extending flange on the rear case so that the joint is protected from water draining down from above. The said parts 5 are secured in position by screws 8.

The wall of the diaphragm inclosing section 3 is formed and arranged so that under the conditions of actual use there will be a drainage pitch whereby water and other 10 particles will tend to gravitate out of the casing cavity into the horn proper and from the latter outwardly to the mouth of the horn. As explained above, the drainage pitch need not be such that the water will 15 tend to find its way out at all times under all conditions of use, since in the case of an automobile proceeding up a steep hill this would require that the inner wall of the case be funnel-shaped with a pitch approxi- 20 mately equal to the pitch of the grade of the road, whereas efficient drainage requires only that such wall be within limits approximately parallel with the diaphragm.

In view of all of the above conditions, it is 25 desirable that the diaphragm be arranged horizontally as shown, that the inner drainage surface of the case be slightly pitched or coned as shown, and that the surface be free from ribs or projections which would tend 30 to prevent escape of foreign matter.

In Fig. 2 is shown a means for securing the horn in a desirable position with respect to a vertical surface on a vehicle, as for instance, the dash board of an automobile. 35 In this case, the securing plate 9 is formed with a support-engaging surface approximately perpendicular to the plane of the diaphragm.

While I have herein fully shown and de- 40 scribed, and have pointed out in the appended claims certain novel features of the construction, arrangement, and operation which characterize my invention, it will be understood by those skilled in the art that 45 various omissions, substitutions, and changes in the forms, proportions, sizes, and details of the device and of its operation, may be made without departing from the spirit of my invention.

50 I claim:

1. In a diaphragm alarm or signal device of the class described, a diaphragm means for securing the device with the diaphragm approximately horizontal, a diaphragm 55 clamp and a tight case for protecting the operating mechanism secured on the upper side of said diaphragm, and, on the lower side of said diaphragm, a co-operating diaphragm clamp and an approximately hori- 60 zontal case wall extending adjacent the lower face of the diaphragm and forming therewith a thin annular space, a downward opening through said case wall, having a mouth piece or horn arranged for project- 65 ing the sound in a direction approximately

parallel with the diaphragm, the inner surface of said lower case wall adjacent said opening being formed so as to have a pitch affording drainage by gravity through the horn opening when the device is supported 70 with the diaphragm approximately horizontal.

2. In a device of the class described, a substantially horizontal diaphragm, a tight upper casing on the upper side of the dia- 75 phragm for protecting the operating mechanism, and on the lower side of said dia- phragm, a diaphragm casing and a curved horn or projector arranged to project the sound in a direction approximately parallel 80 with the diaphragm, said diaphragm casing forming with the lower face of the dia- phragm a thin annular space, the inner surface of the diaphragm casing adjacent the horn opening and the curved horn com- 85 municating therewith being formed and ar- ranged, so as to afford drainage by gravity through said opening and horn when the device is supported so that the mouth of 90 the horn is directed horizontally.

3. In a device of the class described, a substantially horizontal diaphragm, a tight upper casing on the upper side of the dia- 95 phragm for protecting the operating mechanism, and on the lower side of said dia- phragm, a diaphragm casing and a curved horn or projector arranged to project the sound in a direction approximately parallel 100 with the diaphragm, said diaphragm casing forming with the lower face of the dia- phragm a thin annular space, the inner sur- face of the diaphragm casing adjacent the horn opening and the curved horn com- 105 municating therewith being formed and ar- ranged, so as to afford drainage by gravity through said opening and horn when the device is supported so that the mouth of 110 the horn is directed horizontally, together with a bracket formed and arranged for se- curing said device to the dashboard of an automobile in said position with the mouth of the horn forwardly directed.

4. In a device of the class described, a substantially horizontal diaphragm, a tight upper casing on the upper side of the dia- 115 phragm for protecting the operating mech- anism, and on the lower side of said dia- phragm, a diaphragm casing and a horn, or projector extending approximately par- 120 allel with said diaphragm, said diaphragm 125 casing forming with the lower face of the diaphragm a thin annular space, the inner surface of the diaphragm casing opposite the diaphragm being formed so as to have a pitch affording drainage by gravity through the horn opening when the device is supported so that the diaphragm is ap- 130 proximately horizontal together with means for securing said device to the dashboard of an automobile in approximately horizontal

position with the mouth of the horn forwardly directed.

5. In a device of the class described, a substantially horizontal diaphragm, a tight upper casing on the upper side of the diaphragm for protecting the operating mechanism, and on the lower side of said diaphragm, a diaphragm casing and a horn, or projector extending approximately parallel with said diaphragm, said diaphragm casing forming with the lower face of the diaphragm a thin annular space, the inner surface of the diaphragm casing opposite the diaphragm being coned adjacent said opening so as to afford drainage by gravity

through the horn opening when the device is supported so that the diaphragm is approximately horizontal together with means for securing said device to the dashboard of an automobile in approximately horizontal position with the mouth of the horn forwardly directed. 20

Signed at New York city, in the county and State of New York, this 2nd day of December, A. D. 1909.
